I. A. TREIMAN ET AL

LOCK

Filed Dec. 19, 1921

UNITED STATES PATENT OFFICE.

ISAAC A. TREIMAN AND ROBERT L. ROCKWELL, OF SEATTLE, WASHINGTON; SAID ROCKWELL ASSIGNEE OF ONE-FOURTH TO SAID TREIMAN.

LOCK.

Application filed December 18, 1921. Serial No. 583,485.

To all whom it may concern:

Be it known that we, ISAAC A. TREIMAN and ROBERT L. ROCKWELL, a former subject of Russia who has taken out first citizenship papers in the United States and a citizen of the United States, respectively, and residents of the city of Seattle, county of King, State of Washington, have invented certain new and useful Improvements in Locks, of which the following is a specification.

This invention relates to improvements in door locking mechanism, and more particularly to an attachment that may be applied, 15 and locked to the face plate of the ordinary key actuated locking mechanism of a door, or the like, to receive the key and to retain it within the lock in such position that it can not be removed, or turned, by anyone at the side of the door opposite that to which the attachment is applied, or by anyone on the same side on which it is applied, except by one who possesses a suitable key for controlling the attachment 25 locking mechanism.

More specifically, the object of the invention resides in the provision of an attachment of the above character applicable to the inside of a door, and having a key 30 actuated means whereby it may be removably attached to the face plate of the ordinary door lock, and equipped with a rotatably contained barrel wherein the shank and turning end of the key for the door lock, after being applied to the door, may be projected to be held thereby in such position that it can not be removed from the door by the use of my sort of tool in the hands of an unauthorized person.

A further object of the invention is to provide for turning the door key by rotation of the barrel, so that the attachment need not ordinarily be removed, except at times when it is desired to apply the key 45 from the outside of the door.

It is also an object of the invention to provide for locking the barrel against rotation.

In accomplishing these and other objects 50 of the invention, we have provided the improved details of construction, the preferred forms of which are illustrated in the accompanying drawings, wherein—

Figure 1 is a side view of a portion of a

door plate, with an attachment embodying the present invention applied thereto.

Figure 2 is an edge view of the door and lock, and a vertical, sectional view of the attachment, illustrating the manner in which the latter is fixed to the lock cover 60 plate.

Figure 3 is a vertical section of the attachment, taken on the line 3—3 in Figure 2, particularly illustrating the construction of the attachment members and the means for operating the same.

Figure 4 is a rear, view of the attachment.

Figure 5 is a vertical section taken on the line 5—5 in Figure 2.

Figure 6 is a bottom view of the device.

Referring more in detail to the drawings— 70 1 designates a part of a door of the ordinary type, equipped with a mortise lock designated at 2. On opposite sides of the door, face plates 3 and 4 are secured as shown in Figure 1, by means of the screws 5. The lock 2 is equipped with the usual locking mechanism including the bolt 6 which is adapted to be actuated to and from locking position upon the turning of a key 7 which is applied to the lock, as shown in Figure 2, through the key opening 8 in the plate 4.

10 designates, as a whole, an attachment 85 constructed according to the present invention. This consists of a metallic housing 11 having its upper portion formed cylindrically to rotatably contain a barrel 12, and its lower portion likewise formed to rotatably contain a barrel 13. The barrel 12 is provided centrally with a flattened slot 14 adapted to receive therein the shank and end portion 7' of the door key 7 when the device is applied, and the barrel 13 is provided with a slot 15 for receiving a key 16 whereby the barrel may be rotated and which also is for the purpose of actuating certain locking tumblers located within the barrel, and which co-act with other tumblers 9 that are mounted in a block 9 that is secured within the housing intermediate the barrels so that these latter tumblers may be moved to effect the unlocking of the barrels as will presently be described. Each of the barrels 12 and 13 is provided at its inner end with an annular flange which engages against shoulders formed in the base of

the housing to prevent outward movement of the barrels, and a cover plate 17 is secured by screws 19 over the inner face of the housing. The inner end of the barrel 12 is spaced somewhat from the cover plate 17 and is held against inward movement by means of a strip of metal 20 that is fitted within the housing between the plate 17 and the flange of the barrel, as is shown in Figures 1 and 3, while the barrel 13 has, as its inner end, a threaded extension 18 of a truncated, conical form which retains the barrel against inward movement.

The cover plate 17 has a key opening 21 therein located in such position that its center will register in alignment with the round enlargement at the upper end of the key hole 8 of the plate 4 when the device is applied to the door and is provided with flanges 22 and 22' as shown in Figure 4, which extend within this rounded, upper portion of the key hole 8 to thereby maintain the attachment in proper alignment when it is applied.

Pivotedly fixed to the inner face of the cover plate 17, by means of rivets 23 as shown in Figure 3, are paired plates 24-24'. These are disposed on opposite sides of the central, vertical line of the cover plate and have flexible legs 25 extended to engage at their lower ends with opposite sides of the threaded extension 18 on the barrel 13 so that, on rotation of the barrel, the engaging portions of the legs will be caused to follow upwardly on the threads of the extension and will be spread apart thereby and, at the same time, drawn inwardly.

Each of the plates 24 has a hook-like extension 29, see Figures 1, 4 and 6, formed thereon to extend through the cover plate opening 21 and, when the attachment is applied, these hooks will extend within the key hole 8 in such manner that upon rotation of the barrel 13 by the key 16, which spreads apart and draws the plates 24-24' inwardly, they will be caused to engage with the plate 4 at opposite sides of the key hole and will thereby retain the attachment securely fixed to the door. At their upper ends, the plates 24-24' have outturned ears 30 and 30' and supported between these is a compression spring 31 which yieldingly holds the lower leg portions of the plate engaged with the threaded extension of the barrel 13.

The barrel 13 is equipped with a series of locking tumblers, as designated at 35, which co-act with other tumblers 36 in the block 9 in such manner that insertion of the key 16 positions the tumblers to release the barrels so that they are free to be turned. Likewise, removal of the key locks the barrel 13 against rotation. In the barrel 12, at one side of the key slot 14 as shown in Figure 5, are spring pressed tumblers 40 which are adapted, upon rotation of the barrel through

90 degrees, to seat within bores provided for the tumblers 36 to thereby lock the barrel 12 against rotation.

Assuming that the device is so constructed, it is applied and used in the following manner:

The key 7 is first inserted within the lock of the door so that it will assume a position as shown in Figure 2. The attachment is then applied so that the shank of the key projects through the slot in the cover plate 17 and into the slot 14 of the barrel 12. The key 16 is then inserted in the barrel 13 and the barrel is thereby rotated so that the latch plates 24-24' are spread apart and drawn inwardly, so that the hooks 29 engage with the plate 4 and lock the attachment securely in place. The key 16 is then removed and, upon its removal, the tumblers 36 drop into position to retain it locked. Then, when it is desired to lock the door, the operator grips the outer portion of the barrel 12 and rotates it in the direction indicated by the arrow in Figure 5. Since the key 7 can not turn within the barrel, it causes the bolt 6 to be moved to locking position; this being accomplished upon turning the key through an initial angle of 270 degrees, so that the tumblers 40 lock within the block 9 to hold the barrel against rotation. In this position of the barrel, the key 7 is in a position transversely of the opening in the lock and can not be removed.

It is readily apparent that anyone attempting to remove the key from the outside of the door by the use of tools for this purpose, will be unsuccessful, since the barrel is locked against rotation and the key which is held against rotation within the barrel is turned transversely of the key hole.

When it is desired to unlock the door, the operator inserts the key 16 which moves all the tumblers to position to release both of the barrels so that they may be rotated. The barrel 12 may then be turned in the reverse direction indicated by the arrow and the door unlocked.

If it is desired to remove the attachment from the door, the barrel 13 is rotated so that the legs of the latch plates 24 are permitted to retract and the hooks 29 are unseated from the plate 4.

It is further apparent that an attachment of this character can readily be applied to either the outside or inside of a door and when not in use, it may be readily removed.

Having thus described our invention, what we claim as new therein and desire to secure by Letters Patent, is:

1. The combination with a door having a locking mechanism and a key applied thereto and extending from the door, of a locking device independent of the key and adapted to be removably attached to the door and comprising a slotted member for re-

ceiving the extended portion of the key therein and rotatable to actuate the key within the lock.

2. The combination with a door having a locking mechanism and a key applied thereto and extending from the door, of a locking device removably attached to the door and comprising a slotted member for receiving the extended portion of the key therein and rotatable to actuate the key within the lock, and means for locking said member in position to prevent removal of the key from the door.

3. The combination with a door having a locking mechanism, a face plate secured to the door provided with a key hole and a key applied to the locking mechanism through said key hole, of a locking device comprising a housing having expandable means thereon for entering the said key hole to attach the housing to the said plate, a barrel rotatably mounted within the housing having a slot for receiving the extended end of the key whereby the latter is retained against rotation within the barrel, and means for locking the barrel against rotation.

4. The combination with a door, having a locking mechanism, a face plate, provided with a key hole, secured to the door and a key applied to the locking mechanism through said key hole, of a locking device comprising a housing having expandable members extending therefrom for entering the said key hole to attach the device to the face plate, a barrel rotatably mounted in the housing and having a slot for receiving the end of the key whereby the latter is retained against rotation within the barrel, and a key controlled means for actuating the expandable means to attach the device to, or release it from the plate and for locking the barrel against rotation.

5. The combination with a door, having a locking mechanism, a face plate, provided with a key hole, secured to the door and a key applied to the locking mechanism through said key hole and extending from the plate, of a locking device comprising a housing, expandable members secured within the housing having projecting hooks adapted to enter the key hole of the plate, a rotatable barrel within the housing having a slot for receiving the extended portion of the key, a key controlled barrel within the housing having means thereon rotatable with the barrel to expand the attaching members to thereby secure the device to the plate, and means for locking the first named barrel against rotation to retain the door key in such position that it can not be removed.

6. The combination with a door, having a locking mechanism, a face plate secured to the door, having a key hole therein, and a

key for the locking mechanism applied thereto through said key hole and extending from the door, of a locking device comprising a housing adapted to be seated against said face plate and provided with an inner cover plate having an opening in registration with said key hole in the face plate and having flanges adjacent opposite sides of the opening that are projectable into the face plate key hole to retain the attachment in proper alignment, a barrel rotatably fixed within the housing, having a slot aligned with the key hole and cover plate openings to non-rotatably receive the shank and head of the door key therein, a pair of plates pivotally secured within the housing and having extended hook members adapted for projection within the key hole of the door plate, a locking barrel within the housing, having means thereon adapted upon rotation of the barrel to spread the plates to cause the hooked members to effect connection with the door plate, and means within the housing for locking the barrels against rotation and operable upon the insertion of a key within the locking barrel to release both barrels for rotation.

7. The combination with a door, having a locking mechanism, a face plate secured to the door, having a key hole therein, and a key for the locking mechanism applied thereto through said key hole and extending from the door, of a locking device comprising a housing adapted to be seated against said face plate and provided with an inner cover plate having an opening in registration with said key hole in the face plate, a barrel rotatably fixed within the housing, having a slot aligned with the key hole and cover plate openings to non-rotatably receive the shank and head of the door key therein, a rotatable locking barrel within the housing having a threaded conical extension, a pair of plates pivotally fixed to the cover plate, with depending flexible legs engaging opposite sides of said conical extension, and having hooked extensions projected into said key hole of the face plate, a spring for retaining the leg portions of the plates engaged with the conical member, means within the housing for locking the key receiving barrel in position whereby the door key can not be removed from the door, tumblers for holding the locking barrel against rotation; said locking barrel having a key slot wherein a key may be extended to effect the release of both the barrels and whereby the latter may be rotated to effect the spreading apart or contraction of the hooked locking members, for the purpose set forth.

Signed at Seattle, Washington, this 10th day of December, 1921.

ISAK A. TREIMAN.
ROBERT L. ROCKWELL.
